FIG. 1 is a front elevational view of a rear door trim panel for an automobile in accordance with our new design;

FIG. 2 is a top plan view of the rear door trim panel in accordance with our new design of FIG. 1;

FIG. 3 is a bottom plan view of the rear door trim panel in accordance with our new design of FIGS. 1 to 2;

FIG. 4 is a right side elevational view of the rear door trim panel in accordance with our new design of FIGS. 1 to 3;

FIG. 5 is a left side elevational view of the rear door trim panel in accordance with our new design of FIGS. 1 to 4;

FIG. 6 is a front-right side perspective view of the rear door trim panel in accordance with our new design of FIGS. 1 to 5; and,

FIG. 7 is a front-left side perspective view of the rear door trim panel in accordance with our new design of FIGS. 1 to 6. The rear view of the rear door trim panel forms no part of the claimed design.

Our new design includes the mirror image of the rear door trim panel shown in FIGS. 1 to 7.
